UNITED STATES PATENT OFFICE.

JAMES W. LYON, OF BROOKLYN, NEW YORK.

SELF-LIGHTING GAS-BURNER.

SPECIFICATION forming part of Letters Patent No. 423,525, dated March 18, 1890.

Application filed April 23, 1889. Serial No. 308,307. (No model.)

To all whom it may concern:

Be it known that I, JAMES W. LYON, of Brooklyn, county of Kings, and State of New York, have invented certain new and useful 5 Improvements in Self-Lighting Gas-Burners, of which the following is a full, clear, and exact description, reference being had to the accompanying drawings, and to the letters of reference marked thereon.

10 My improvements relate to that class of burners commonly called "self-lighting" gas-burners," wherein provision is made for maintaining (when desired) a very small flame, to increase which it is only necessary to turn on 15 the gas to any desired extent.

Among the objects of my invention are the provision or production of a burner of the class named wherein the operating parts are few and simple, easy of construction, and not 20 liable to get out of order; wherein the auxiliary gas-channel can neither become clogged nor be closed until the principal channel is well opened; wherein the principal and auxiliary channels and the passage through the key 25 are so arranged that both said channels cannot be closed at the same time, and thus the light extinguished by any rapid movement of the key; wherein the flame (when the light is turned down) shall be well protected from 30 disturbance by passing air-currents, and wherein other advantages in the matters of construction, operation, and use shall be secured, as will appear from the following description:

35 To accomplish these objects, my improvements involve certain new and useful arrangements or combinations of parts and peculiarities of construction, all of which will be first fully described, and then pointed out 40 in the claims.

In the accompanying drawings, forming part of this specification, Figure 1 is a view in elevation of my improved burner, showing the flame-protector closed, as when the light 45 is turned down; and Fig. 2 is a similar view showing the protector opened, as when the light is turned on full. Fig. 3 is an elevation showing the side opposite Fig. 1, and Fig. 4 a similar view showing the side opposite Fig. 50 2. Fig. 5 is a sectional elevation of the burner upon a flame at right angles to the axis of the key, and Fig. 6 a similar view upon

a plane through said axis. Fig. 7 is a side view of the key detached from its seat, and Figs. 8 and 9 details of modified keys. 55

In all the figures like letters of reference, wherever they occur, indicate corresponding parts.

A is the tip of the burner, which is preferably of lava and removable, but which may 60 be of any character and material.

B is the body of the burner, which is preferably in one piece, embodying the seat for the tip, the key-seat, and the threaded base for application to any burner-seat. 65

Within the body of the burner are the gas-channels *a*, *b*, and *c*, of which *a* is the supply-channel, (in this form always open,) *b* the principal channel, through which gas is fed when the light is turned up, and *c* the auxiliary channel, through which the gas must 70 pass when the flame is turned down sufficiently. It should be observed that these channels are all in a position to be easily drilled from the exterior of the burner, and they are all straight and amply large to obviate any clogging up, or to otherwise impede the desirable free flow of gas. 75

C is the gas-key, which is fitted to its seat in the body of the burner. It is of tapering 80 form to insure an accurate fit, and is provided upon the small end with a lever *D*, held in place by a nut *d*, or equivalent means, such as a pin. Chains or cords, as *E* *E*, of any length, are applied to the lever for moving 85 the key. A suitable stop-pin or projection, as *F*, prevents the lever from being turned too far in either direction, and a light spring, as *e*, between the body *B* and lever *D* insures, always, a firm seating of the key. A gas-channel *f* is formed in the key by cutting in from one side a trifle past the axis. This is best shown in Fig. 7. It affords an abundant gasway, at the same time leaving sufficient uncut stock to close the channels in the 95 manner desired, and does not (when the channels are located in the burner, as shown) require that any additional channels be formed in the key, as is required in other forms of these self-lighting burners. The lever *D* is 100 mounted on the key in such relation with the channel *f* and with the stop *F* that the stock or uncut portion of the key cannot be brought around to close the inlet-channel *a*, and the

bearing-surface of the stock is of such extent that it cannot cover or close both channels *b* and *c* at the same time. In other words, assuming the flame to be turned up completely, 5 the channel *b* cannot be closed until the auxiliary channel *c* is fully opened, and then the flame cannot be turned up, except by admitting gas to channel *b* before channel *c* is closed. Thus it will be apparent that the gas 10 under all circumstances escapes to the tip, where it is burned, and a flame is always maintained ready to be turned up or turned down, according to circumstances. No sudden turning 15 of the key can interrupt the flow of gas to any such extent as to extinguish the flame, and the flame cannot therefore be "snapped" out, as is a common occurrence in other burners of this class.

Instead of cutting the key as shown in Fig. 20, the gas-passage in it might extend only a little beyond the surface for the requisite distance around the circumference, as at *f*, Fig. 8. This would leave more metal in the key, but would in no way modify its operation 25 in controlling the escape of gas. Again, instead of cutting a channel in the key, as shown in either Figs. 7 or 8, a portion of the key might be cut away, as shown at *f'*, Fig. 9, and the remaining stock pierced, as at *f''*, 30 same figure. Such a key, being located in the burner-body, with the channels arranged as shown, would also secure all the advantages of the previous forms shown.

The flame-protector is made in two sections 35 *G G*, hinged on each side of the burner-body, as at *g g*, and these sections are arranged to close about the top of the burner, as in Figs. 1 and 3, when the flame is turned down, and 40 to be swung down out of the way of the flame when the latter is turned up. These sections may be wholly of metal or of any other material, and they may, if desired, be provided with mica or other transparent or semi-transparent panes, as *h*, through which the flame 45 may be observed when they are closed. The top of the protector *i i* is shown as inclined upwardly to direct passing air-currents above and away from the flame; but the top may be otherwise formed or altogether 50 omitted, if desired. The sections of the protector are simultaneously operated to open and close them by links *k k*, pivoted to the sections near the hinge *g* on the side opposite the lever *D*, and at their other ends eccentrically pivoted on the key *C*, as at *l*. By 55 this arrangement whenever the key is turned the protector is opened or closed accordingly as the gas is turned on or off, the pivot *l* being properly located with respect to the channel for that purpose. The sections, being made to open in the manner explained, offer no detrimental obstruction to the light, are not liable to be damaged by the flame, do not create any up or down draft by which the

small flame may be extinguished, as in the 65 case of a vertically-adjustable globe or flame-protector, and they do not require that the burner be elongated to accommodate any vertical movement of the protector, but rather enable me to construct the burner with the 70 limits of length of ordinary gas-burners. The links might be pivoted on lever *D*. At *H* is a regulating-screw entering the channel *c*, by means of which the amount of gas passing 75 through that channel, and thus the size of the small flame, may be governed, as will be readily understood.

The body of the burner is of very simple form. It does not require that it be cast with various lugs or projections to accommodate 80 auxiliary channels or by passes, but may be made from bar metal, the circular parts being turned, and the exterior thus left smooth and appropriate for use in connection with a polished chandelier or bracket. 85

Having thus fully described my invention, what I claim as new herein, and desire to secure by Letters Patent, is—

1. In a self-lighting burner, the combination of the burner having the supply openings or passages, the key seated in the burner and having a groove adapted to communicate with said passages, the protector consisting of the two parts pivoted to the burner, the links having their upper ends connected 90 to the protector and their lower ends pivoted together eccentrically to the key, substantially as and for the purpose described.

2. In a self-lighting burner, the combination of the burner, the key seated in said burner, the protector consisting of the two members pivoted at their lower ends to the burner, the links having their upper ends connected to the members of the protector near the pivot thereof, and their lower ends 100 eccentrically connected to the key, substantially as described.

3. In a self-lighting gas-burner, the combination of the burner, the key seated therein, the lever connected to one side of the key, 110 the spring for retaining the key and lever, the stop or projection on the burner for limiting the movement of the lever, the protector consisting of the two members having their lower ends pivoted to the burner, and the links having their upper ends connected to the members of the protector and their lower ends eccentrically connected to the key, all 115 arranged and adapted to operate substantially as described. 120

In testimony that I claim the foregoing I have hereunto set my hand in the presence of two witnesses.

JAMES W. LYON.
